UNITED STATES PATENT OFFICE

OTHO V. KEAN, OF PROVIDENCE, RHODE ISLAND.

BULLET.

1,219,742.

Specification of Letters Patent. Patented Mar. 20, 1917.

Application filed March 25, 1916. Serial No. 86,567.

To all whom it may concern:

Be it known that I, OTHO V. KEAN, a citizen of the United States, residing at Providence, in the county of Providence and State of Rhode Island, have invented certain new and useful Improvements in Bullets, of which the following is a full, clear, and exact description, such as will enable others skilled in the art to which it appertains to make and use the same.

This invention relates to bullets, and more particularly to small arms bullets of the hard jacketed type.

It has heretofore been customary, in the manufacture of such ammunition, to employ a jacket of tough metal drawn to shape and subsequently filled with a lead core. A jacket so made has required successive drawing and annealing operations and difficulties entailing expense have been encountered in insuring a uniform thickness of metal throughout the product.

The primary object of this invention is to provide an improved bullet of the type mentioned which is capable of expeditious and relatively cheap manufacture.

Other objects and advantages will be in part noted hereinafter in connection with the following description of a typical embodiment of the invention illustrated in the accompanying drawing, wherein—

Figure 1 is a perspective view of the improved bullet;

Fig. 2 is an end view;

Fig. 3 is a side view of a section of the jacket; and

Fig. 4 is an end view thereof showing a slightly modified form.

The invention comprises, in general, a bullet having a hardened jacket divided into complementary sections formed of stamped metal and held together by insertion of a soft metal core.

Referring more particularly to the drawing, the bullet is provided with a jacket, preferably of a conoidal form, divided longitudinally into two complementary sections 1 and 2, these sections being arranged relative to each other transversely circumferentially of the bullet. The sections 1 and 2 are of stamped metal, having smooth exteriors and turned longitudinal ribs or flanges 3 which fit together and interlock with the core to retain the sections in position relative to each other.

The core of the bullet is preferably of

lead or other readily fusible metal, which is poured into the jacket when the sections of the latter are held together, thereby anchoring the flanges 3 securely together. It is to be noted that the jacket sections are capable of expeditious manufacture from rolled plates of suitable material, usually a nickel copper alloy, such practice permitting of the sections being made integral longitudinally of the bullet for the full length of the jacket, this longitudinal continuity of the sections affording a substantial compressive strength thereof longitudinally, the bullet thereby offering great resistance to mushrooming. If desired, the inner edges of the flanges 3 of the jacket sections may be roughened or corrugated, as indicated at 4 in Fig. 3, and further the inner surface of the sections may be scored slightly, as indicated at 5 in Fig. 4, in order to afford a better gripping surface for the lead core when inserted.

Bullets made, as described, are efficient in service and will not produce the dum-dum effect, the flanges 3 stiffening the jacket longitudinally. Furthermore, all the advantageous characteristics of the ordinary jacketed bullet are retained, while the manufacturing and assembling cost thereof is materially reduced.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a bullet, a jacket composed of longitudinally disposed sections arranged transversely circumferentially of the bullet relative to each other.
2. In a bullet, in combination, a core, and a longitudinally sectional jacket therefor having longitudinally disposed internal stiffening ribs.
3. In a bullet, in combination, a core, and a conoidal jacket therefor composed of sections relatively transversely circumferentially arranged and anchored together by said core.
4. In a bullet, in combination, a core, a

- hard metallic jacket therefor composed of sections relatively transversely circumferentially arranged, and longitudinally disposed internal projections on said sections, 5 said core anchoring said sections together.
5. In a bullet, in combination, a core, a hard metallic jacket therefor composed of sections relatively transversely circumferentially arranged, and longitudinally disposed 10 and abutting internal projections on said sections, said core anchoring said sections together.
6. In a bullet, in combination, a jacket composed of hard stamped metal sections 15 relatively transversely circumferentially arranged, internal longitudinal flanges on said sections abutting each other respectively, and a filling coöperating with said flanges to anchor said sections together.
- 20 7. In a bullet, in combination, a jacket composed of hard stamped metal sections relatively transversely circumferentially arranged, internal longitudinal flanges on said sections abutting each other respectively, 25 and a filling coöperating with said flanges to anchor said sections together, portions of the inner face of said jacket being roughened to securely grip said core.
8. In a bullet, in combination, a jacket 30 composed of stamped metal sections respectively integral longitudinally of the bullet for the length of the jacket.

9. In a bullet, in combination, a jacket composed of stamped metal sections respectively integral longitudinally of the bullet 35 for the length of the jacket, and a core, said sections having internal projections adapted to interlock with said core to anchor said sections in position relative to each other.
10. In a bullet, in combination, a jacket 40 composed of stamped metal sections respectively integral longitudinally of the bullet for the length of the jacket, said sections having internal flanges, the flanges of one section abutting those of another section, 45 and a filling for said jacket with which the said flanges coöperate to anchor said sections in position relative to each other.
11. In a bullet, in combination, a jacket composed of stamped metal sections respectively integral longitudinally of the bullet 50 for the length of the jacket, said sections being arranged transversely circumferentially of the bullet relative to each other.
12. In a bullet, in combination, a core, and a jacket therefor comprising sections relatively transversely circumferentially arranged, and anchored together by said core.

In testimony whereof I affix my signature, in the presence of two witnesses.

OTHO V. KEAN.
